WINDOW CONSTRUCTION

Jay D. Silberman, Scarsdale, N. Y.

Application April 8, 1937, Serial No. 135,611

20 Claims. (Cl. 20—52.6)

The present invention relates to an anti-rattling device for a window of the type, which is raised or lowered through the operation of a regulator handle.

Among the objects of the present invention is to provide a device of the general character described, which is simple and inexpensive to manufacture, which normally holds the window against rattling in any slide position thereof, which is automatically releasable upon a manipulation of the regulator handle to permit the easy raising or lowering of said window, and which is concealed from view so that the neat and pleasing appearance of the window construction is preserved.

Another object is to provide an anti-rattling device which is particularly adapted for use with the window constructions of motor vehicles, and which can be co-ordinated with the conventional type of slide window and window regulator.

In a specific embodiment of the invention there is provided a wedge, between the casing and the side of the window, which is normally urged into firm frictional engagement with said window, which is moved out of anti-rattling engagement by the usual inward impulse naturally imparted to a window regulator handle during the rotation thereof, and which is automatically returned to anti-rattling engagement with said window, in any slide position of adjustment of the latter.

In the accompanying drawing in which is shown one of various possible embodiments of the several features of the invention,

Fig. 1 is a vertical section with part broken away, taken through a window construction embodying the present invention.

Fig. 2 is a section taken on line 2—2 of Fig. 1.

Fig. 3 is a perspective showing part of the anti-rattling device.

Fig. 4 is an enlarged section taken on line 4—4 of Fig. 1, and

Fig. 5 is a section taken on line 5—5 of Fig. 1.

The invention is shown embodied in a conventional motor vehicle side door construction, the frame casing of which includes a pair of uprights, 10, a bottom cross piece 11, a lintel 12, and a horizontal bracing made up of bars 13 and 14 which form a window sill and which define the lower edge of a window opening 15.

A conventional window pane 18 of thick glass is lodged in the window frame between the two bracing bars 13 and 14, and its side edges travel along longitudinal guide tracks 38 when said pane is raised or lowered. Secured to the frame

uprights 10 are the cover plates 16 stamped inwardly at the upper end to form the window opening 15, and forming therebetween below the bracing bars 13 and 14 a housing 17, within which are concealed the pane tracks and the window operating mechanism to be described below.

The window 18 may be raised or lowered through a conventional regulator device including a crank handle 19, mounted upon the outer end of a shaft 20, which is supported upon a bracket plate 21, secured by screws 21a to brace rod 14. Shaft 20 carries a pinion 22 meshing with a segmental gear 23, fixed to a stub shaft 24 also supported on said bracket plate. This segmental gear 23 is provided at one end with a lifter arm 25, pivotally connected at its outer end to one end of a link 26, the other end being pivotally connected to the middle of a rail or channel 27, secured to the lower edge of the glass pane 18. The weight of the glass pane 18 is counterbalanced by a spiral spring 30 acting on the stub shaft 24.

The construction so far described is old and conventional, and forms per se no part of the present invention.

The anti-rattling device includes a pair of elongated wedges 34, fixed to the frame uprights 10 against longitudinal movement, and co-acting with elongated slide wedges 35. The two co-acting wedges 34 and 35 on each side of the window frame are reversely disposed with the butt of the wedge 34 on top, and the butt of the wedge 35 on the bottom, the inclined surfaces 36 and 37 of said wedges 34 and 35 being in sliding engagement. The inner sides of the wedges 35 facing the sides of the window pane, have secured thereto, or are provided with channels 38 which form runways for said window pane, and which are maintained in parallelism irrespective of the slide position of said wedges 35.

The slide wedges 35 are normally urged upwardly and into firm frictional engagement with the sides of the window 18 in any slide position thereof by expansible coil springs 39, the lower ends of which extend into recesses 40 formed in blocks 41 fixed to the bottom of the window frame, and the upper ends of which extend into plunger sleeves 42 press fitted into recesses 43 formed in the lower ends of the slide wedges 35. The upward pressure of the springs 39 on the wedges 35, causes said wedges to slide upwardly on the inclined surfaces 36 of the wedges 34, so that said wedges 35 are moved inwardly into frictional anti-rattling engagement with the sides of the pane 18.

To release the anti-rattle friction hold to permit opening or closing of the window, means is provided to move the slide wedges 35 downwardly against the resistance of springs 39, and out of frictional engagement with the sides of the pane 18. For this purpose a push rod 44 is provided, preferably extending axially through shaft 20, which is made hollow for the purpose. The outer end of rod 44 impinges the crank handle 19, which is hinged at 45 to said shaft 20, the inner end being pivotally connected to one end of an arm 46, having its other end affixed to a horizontal rock shaft 47 supported within the housing 17 by bearing clips 48 secured to the window frame. Arms 49 are affixed to the outer ends of rock shaft 47, and are pivotally connected at their outer ends to the respective slide wedges 35, which are formed with recesses 50 to accommodate said arms and permit relative rotatable movement thereof with respect to said slide wedges.

The cover plates 16 are provided at their upper ends with the conventional side sections 52, defining the sides of the opening 15, and forming 25 with the uprights 10 housings for the wedges 34 and 35, and guideways for the wedges 35 in their longitudinal movements, said housings being preferably lined with strips 52a and 52b of suitable material such as wood.

30 The hinged mounting of the crank regulator handle 19 on the outer end of the pinion shaft 20, permits said handle to be swung inwardly about the pivot point 45. The outward movement of the handle 19 about the pivot point 45 is 35 preferably limited by a flange 53, formed on said handle, and normally engaging the inner side of a flange stop 54 formed on the lower side of the outer end of the pinion shaft 20.

The instinctive inward impulse naturally imparted to the crank handle 19 in a direction substantially parallel to its axis of rotation upon rotation thereof, causes said handle to swing inwardly about the pivot point 45 and causes the corresponding inward movement of the push rod 44. 45 This causes the counterclockwise rotation of the rockshaft 47 as viewed in Fig. 4, which in turn causes the downward movement of the slide wedges 35, against the action of the coil springs 39, and along the inclined wedge surfaces 36 so that 50 said slide wedges will be moved outwardly out of frictional engagement with the window 18. This permits the window to be easily raised or lowered without the hampering action of the anti-rattling device. When the inward pressure on the handle 55 19 is relieved the springs 39 will automatically move the slide wedges 35 upwardly and inwardly into firm frictional anti-rattling engagement with the sides of the window pane 18 in any slide adjusted position of the latter.

60 It should be noted that my anti-rattling device is simple and inexpensive to manufacture, can be utilized with conventional type of automobile window construction and window regulator device, has no window attachment which would add 65 weight to the window and render the raising or lowering of said window comparatively difficult, is entirely concealed within the housing 17, so that it does not detract from the pleasing and attractive appearance of the window construction, is automatically releasable through the operation of the regulator crank handle thereby dispensing with the use of any such special instrumentalities as finger pieces or the like, and also serves to exclude rain and draft when the window 70 is entirely closed.

An incidental advantage of the construction disclosed, is that the anti-rattle wedge prevents forcing the window to open position from the outside of the car, and so affords reasonable assurance against theft, even though the windows, 5 when the vehicle is parked, are not completely closed.

Although the invention is shown embodied in a door construction of a motor vehicle, as far as certain aspects of the invention are concerned 10 said invention may be incorporated in any other window construction of the slide type.

It will thus be seen that there is herein described apparatus, in which the several features of this invention are embodied, and which apparatus in its action attains the various objects of the invention, and is well suited to meet the requirements of practical use.

As many changes could be made in the above construction, and many apparently widely different embodiments of this invention could be made without departing from the scope thereof, it is intended that all matter contained in the above description or shown in the accompanying drawing, shall be interpreted as illustrative and not in 25 a limiting sense.

Having thus described my invention, what I claim as new and desire to secure by Letters Patent is:—

1. A window construction including a slide 30 window, a crank handle for raising or lowering said window, means for mechanically holding said window against rattling, and means actuated by the normal pressure impulse imparted to said handle in turning the same, for releasing 35 said holding means, to permit the lowering or raising of said window by the operation of said handle.

2. A window construction including a slide window, means for holding said window against 40 rattling, a rotatable handle for raising or lowering said window, and means actuated upon an impulse imparted to said handle in a direction substantially parallel to the axis of rotation of said handle for releasing said holding means, to 45 permit the raising and lowering of said window upon the operation of said handle.

3. A window construction including a slide window, means for normally holding said window in any slide position thereof against rattling, 50 means including a rotatable handle for mechanically raising or lowering said window, means actuated upon the initial pressure impulse imparted to said handle serving to release said holding means to permit the free slide movement of said window upon rotation of said handle, and means for effecting automatic reengagement of said holding means into anti-rattling position upon interruption of said impulse.

4. A window construction including a slide 60 window, a movable wedge normally urged into frictional engagement with said window to hold the same against rattling, a crank handle for raising or lowering said window, and means actuated by the normal pressure impulse 65 imparted to said handle, for moving said wedge out of frictional engagement with said window, to permit said window to be lowered or raised upon operation of said handle.

5. A window construction including a housing 70 at one end and having a window opening at the other end, a window slidably adjustable between said opening and said housing, means for holding said window against rattling, a crank handle for mechanically raising or lowering said window, a 75

- transmission between said handle and said holding means concealed within said housing, and means actuated by the normal pressure impulse imparted to said handle for actuating said transmission means to release said holding means.
- 5 6. A window construction including a housing at one end and having a window opening at the other end, a window slideable between said opening and said housing, a slide wedge normally urged into frictional engagement with said window to hold it against rattling, a handle, transmission means concealed within said housing and operated from said handle for raising and lowering said window, and a second transmission means between said handle and said slide wedge concealed within said housing and under control of the handle in the initial part of said movement for shifting said wedge out of frictional engagement with said window to permit the raising or 10 lowering of said window.
- 10 15 7. A window construction including a housing at one end and having a window opening at the other end, a window slideable between said opening and said housing, means for holding said window against rattling, a crank handle for mechanically raising or lowering said window, a rock shaft concealed within said housing, a transmission between said handle and said rock shaft for rotating said shaft in one direction upon normal pressure impulse imparted to said handle, and transmission means in said housing between said rock shaft and said holding means for releasing said latter means upon rotation of said shaft.
- 20 25 8. In a window construction of the class in which there is included a frame casing having a pair of spaced plates forming a housing therebetween, and having a window opening above said housing, a window slideable between said opening and said housing means for holding said window against rattling, and a crank handle for raising and lowering said window; a mechanical transmission means between said handle and said holding means concealed within said housing for releasing said means, to permit the raising or lowering of said window.
- 30 35 40 45 9. A window construction including a pair of side frame uprights, a pair of wedges fixed respectively to said uprights against longitudinal movement with respect thereto, a pair of slide wedges co-acting with said fixed wedges respectively, a window between said slide wedges, means normally urging said slide wedges into firm frictional engagement with said window to hold said window against rattling, an operating member for raising or lowering said window, means actuated by the normal impulse imparted to said operating member for moving said slide wedges out of frictional engagement with said window to permit the raising or lowering thereof, and means for automatically returning said slide wedges into frictional anti-rattling engagement with said window upon interruption of said impulse.
- 50 55 60 65 10. A window construction including a slide window, a wedge normally urged into frictional engagement with said window to hold said window against rattling, a handle having a single grip portion and serving in the operation thereof for raising or lowering said window, a rock shaft, a transmission between said handle and said rock shaft for rotating said shaft in one direction upon initial impulse imparted to said handle, and transmission means between said rock shaft and said wedge to move said wedge out of frictional engagement with said window upon the rotation of said shaft in said direction.
- 70 75 11. A window construction including a slide window, a wedge fixed against longitudinal movement and having an inclined surface facing the side of said window, a slide wedge having an inclined surface engaging the inclined surface of said fixed wedge, a spring at one end of said slide wedge urging said latter wedge longitudinally into frictional engagement with said window, a handle for raising or lowering said window, and means actuated upon an impulse imparted to said handle, for moving said slide wedge longitudinally against the action of said spring and out of frictional engagement with said window.
12. A window construction including a slide window, a pair of co-acting wedges on one side of said window having interengaging inclined surfaces, one of said wedges being longitudinally slideable along the inclined surface of the other wedge, spring means normally urging said slide wedge into frictional engagement with one side of said window to hold said window against rattling in any slide position thereof, a crank handle for raising or lowering said window, and means actuated by the normal pressure impulse imparted to said handle in turning the same for moving said slide wedge against the action of said spring means, and out of frictional engagement with said window to permit said window to be lowered or raised by the operation of said handle.
- 15 20 25 30 13. A window construction including a slide window, means for holding said window against rattling, a crank handle for raising or lowering said window, a push rod axially moved in one direction by an impulse imparted to said crank handle in a direction substantially parallel to the axis of rotation thereof, and transmission means interlinking said push rod and said holding means for releasing said latter means upon the axial movement of said rod.
- 35 40 45 50 55 14. A window construction including a slide window, two pairs of co-acting wedges on opposite sides of said window respectively, each pair including a wedge fixed against slideable movement, and a longitudinally slideable wedge, spring means normally urging said slideable wedges into frictional engagement with the sides of said window, a crank handle for raising or lowering said window, a push rod actuating axially by an inward impulse imparted to said handle, and transmission means between said push rod and said slideable wedges for moving said wedges longitudinally against the action of said spring means, and out of frictional engagement with said window.
- 60 65 70 75 15. A window construction including a slide window, a wedge fixed against longitudinal movement and having an inclined surface, a slide wedge having an inclined surface engaging the inclined surface of said fixed wedge, a spring at one end of said slide wedge urging said latter wedge into frictional engagement with said window, a push rod, and means responsive to the axial movement of said push rod in one direction for moving said slide wedge longitudinally against the action of said spring and out of frictional engagement with said window.
- 80 85 90 95 16. A window construction including a slide window, means for holding said window against rattling, a hollow shaft, a crank handle hinged to the outer end of said shaft, a transmission between said shaft and said window for raising or lowering said window upon rotation of said shaft, a push rod extending axially through said hollow shaft and urged axially into end engage-

ment with said handle whereby said rod is pushed axially inwardly upon an inward impulse imparted to said crank handle, and means inter-linking said push rod and said holding means for releasing said latter means upon the inward axial movement of said rod.

17. A window construction including a frame structure, a slide window, means for holding said window against rattling, a hollow shaft supported 10 on said frame structure, a crank handle hinged to the outer end of said shaft, a transmission between said shaft and said window for raising or lowering said window upon rotation of said shaft, a push rod extending axially through said 15 hollow shaft and urged axially into contact with said handle whereby said rod is pushed axially inwardly upon an inward impulse imparted to said crank handle, a rock shaft, an arm fixed to said rock shaft and pivotally connected to said 20 push rod for effecting the rotation of said rock shaft in one direction upon the inward axial movement of said push rod, and transmission means between said rock shaft and said holding 25 means for effecting the release of said holding means upon the rotation of said rock shaft, to permit the raising or lowering of said window.

18. A window construction including a slide window, a wedge normally urged into frictional engagement with said window to hold said window against rattling, a crank handle for raising or lowering said window, a rock shaft, a transmission between said handle and said rock shaft

for rotating said shaft in one direction upon normal pressure impulse imparted to said handle in turning the same, and an arm affixed at one end to said rock shaft and pivotally connected at its other end to said wedge to move said wedge out of frictional engagement with said window upon the rotation of said shaft in said direction. 5

19. A window construction including a slide window, a pair of wedges on opposite sides of said window normally urged into frictional engagement with said window to hold said window against rattling, a crank handle for raising or lowering said window, a rock shaft, a transmission between said handle and said rock shaft for rotating said shaft in one direction upon normal 10 pressure impulse imparted to said handle in turning the same, and a pair of arms affixed near opposite ends of said rock shaft, and pivotally connected respectively to said wedges to move said wedges out of frictional engagement with 15 said window upon the rotation of said shaft in said direction. 20

20. A window construction including a slide window, a wedge on one side of said window having a channel connected thereto forming a runway for said window, means normally urging said wedge into frictional engagement with said window to hold said window against rattling, and means for moving said wedge out of frictional engagement with said window to permit said 25 window to be raised or lowered. 30
